E. H. MARCY

HYPODERMIC UNIT

Filed Aug. 9, 1922

Inventor
E. H. Marcy.
By Right Dear Lucy May
Atty's.

UNITED STATES PATENT OFFICE.

ERNEST H. MARCY, OF FRAMINGHAM, MASSACHUSETTS.

HYPODERMIC UNIT.

Application filed August 9, 1922. Serial No. 580,615.

To all whom it may concern:

Be it known that I, ERNEST H. MARCY, citizen of the United States, residing at Framingham, in the county of Middlesex and State of Massachusetts, have invented new and useful Improvements in Hypodermic Units, of which the following is a specification.

The object of the present invention is to provide a hypodermic unit in the form of a collapsible tube with a hollow needle to enable the contents of such tube to be injected into the tissues of a patient, intravenously, intramuscularly, or subcutaneously.

Allied with this object is that of providing sealed collapsible containers of the same sort as that embodied in the unit just referred to which may be used by the surgeon in turn with a single needle, which is preserved when a collapsible container has been emptied and thrown away. In the case of the unit, on the other hand, the needle is of inexpensive construction and is discarded with the container after a single use.

A further object has been to furnish as the collapsible tube of such unit one which is hermetically closed prior to use and may be put into connection with the tubular needle just prior to use by a simple and easily accomplished manipulation, and in a way which prevents leakage and excludes entrance of foreign matter, including even minute organisms.

The combination in which the invention consists includes two principal embodiments, as above indicated, the nature and characteristics of which can best be explained in connection with a detailed description thereof. Such description is given in the following specification with reference to the drawings.

In the drawings,

Figure 1 is a longitudinal section through a unit comprising the collapsible capsule and hypodermic needle.

Figure 2 is an elevation partly in section showing the cap removed and the needle in

operative position relative to the capsule.

Figures 3 and 4 are perspectives showing different forms of needle.

Figure 5 is a sectional view of the collapsible tube detached from the needle and cap.

The combination of collapsible container and tubular needle which I call my unit hypodermic syringe consists of a collapsible tube *a* and a needle *b*, which are assembled at the manufacturing laboratory, where the tube is filled with medicine, and each is shipped as a sealed, sterile package ready for instant use upon removal of the seal. Said package comprises not only the collapsible tube and needle above described, but also a cap *c* which encloses the needle and excludes moisture, dust, microorganisms, and other foreign matter therefrom.

As prepared for delivery to the user, the tube and needle are out of communication with one another, and the tube is hermetically closed. The closure in its neck *a'* consists of a partition *a''*, while the closure at the opposite end consists in pinching together the walls of the tube after filling, folding them, and applying any additional holder or seal which may be suitable to make a sufficiently tight joint.

Preferably the tube is made of pure tin, a metal which is ductile and easily worked and to which it is possible to give the formation of the thin walls of a tube with a neck of thicker and more rigid construction, in which an integral and impervious partition may be formed. My protection, however, is not limited to the use of this particular material, as I may use any other material which is capable of being formed or shaped in the manner described, is not subject to attack by the contained medicine, and is capable of being sterilized. The partition *a''* is located at a substantial distance from the open end of the neck, and a space within the latter, outside of the partition, contains a quantity of sealing material *d*. This sealing material may be a plug of soft rubber composition or a compound of wax having sufficient elasticity to close tightly

around an inserted needle, or gelatin or any other material which can be penetrated by a needle, which will permit endwise movement of the needle enclosed within it, and which, when pierced, will not maintain an open passage clear of the needle, but will close in around the needle so as either to prevent leakage outward of the contents of the package, or flow inward of foreign matter.

The needle *b* is secured in a sleeve or bell *e*, which latter is essentially a tube or thimble having an end wall at one end, in which the needle is secured, and being open at the other end, whereby it may be slipped on the neck of the tube. The sides of the sleeve or bell are slotted inward from the open end at a sufficient number of points to make the intermediate material flexible and springy so that it may be slipped upon a tube neck and grip the latter tightly, even though the dimensions and shape of the neck do not correspond exactly with those of the sleeve. The slots are indicated at *f*, and they terminate enough short of the said end wall to leave an uncut or integral zone of the sleeve surrounding the tube neck, even when the sleeve is pushed only part way on the neck.

Referring again to the needle, it is not only pointed at its outer extremity, as usual, in order to penetrate living tissue, but its inner end also extends through the closed end of the sleeve *e* and likewise is pointed. When assembled with the tube at the manufacturing laboratory the sleeve is slipped only part way on the neck, and left where the inner point of the needle is near the wall *a*², but does not penetrate it.

In the bore of the needle is placed a stylet for the purpose of excluding the sealing material from such wall when the needle is applied to the tube. The cap *c* is placed over the needle and sleeve and the cap encloses the needle and sleeve, together with the outer end of the stylet. The unslotted zone of the sleeve previously referred to makes close contact on its interior with the neck of the tube, and on its exterior with the enclosing cap, whereby all possible avenues for admission of moisture or other foreign matter to the needle are closed.

This entire combination is thus guarded from contamination by septic substances or matter which might corrode the needle, wherefore after being made sterile it continues in that condition indefinitely. When used, all that the surgeon needs do is to remove the cap and push the needle-holding sleeve as far down the tube neck as it will go and then withdraw the stylet. When the sleeve is thus pushed down, the inner end of the needle punctures the wall *a*² and passes into communication with the interior of the tube. Then, upon withdrawal of the stylet,

everything is in readiness to inject the contents of the tube. The same construction of tube may be filled, closed, sterilized and marketed independently of the needle, and used by physicians and surgeons in connection with a separate needle which the practitioner may keep for use repeatedly with different tubes. Such needle is shown in Figure 4, and is combined with a holder *e*' essentially like the holder *e* first described and differing only in that it is of stronger construction and more easily handled. It has slots *f* as already described, and in addition a bead *g* by which it may be grasped in being applied or removed from the neck of the tube. Preferably the needle and sleeve are of non-corrodible metal for obvious reasons.

What I claim and desire to secure by Letters Patent is:

1. A hypodermic combination comprising a collapsible tube having a neck with an integral partition between the inner and outer extremities of said neck, forming a chamber at the outer end of the neck adapted to receive a packing, a sleeve or bell open at one end and closed at the other adapted to slip on the exterior of said neck, and a tubular needle secured in the closed end of the sleeve and having an inwardly projected pointed end adapted to enter the neck of the tube and puncture said partition when slipped back on the neck.

2. The combination as set forth in claim 1 including also a body of sealing material occupying the space in said neck outside of said partition and adapted to seal the needle after passage of the latter through said partition.

3. A collapsible metal tube as a medicine container, having a neck provided with an integral cross-wise partition adapted to be punctured by a needle and located back from the open outer end of said neck to provide a packing receiving chamber.

4. A collapsible metal tube as a medicine container, having a neck with an integral crosswise partition, said partition being set back from the open end of said neck, and the interior space of the latter on the outer side of the partition containing a needle-sealing composition.

5. A hypodermic unit consisting of a collapsible tube having a neck with an internal transverse partition across it, a sleeve having a closed and an open end, with slots in its walls extending from such open end fitted slidingly on said neck, a hollow needle secured in said closed end having an inner pointed end projecting toward the open end of the sleeve; said sleeve being slipped part way on said neck and located with the inner pointed end of the needle wholly outside of the partition but adapted to be slipped further along the neck whereby said needle end is caused to penetrate the partition.

6. The hypodermic unit as set forth in claim 5, in which the sleeve has an unslotted zone which surrounds the tube neck, and 10
claim 5, comprising also a cap embracing said sleeve and enclosing the needle.
7. The hypodermic unit as set forth in 5 claim 5, in which an unslotted zone of the sleeve surrounds the tube neck to exclude
foreign matter from the interior thereof.
8. The hypodermic unit as set forth in claim 5, in which the sleeve has an unslotted zone which surrounds the tube neck, and 10
said unit comprises also a cap enclosing the needle and embracing said unslotted zone.
In testimony whereof I have affixed my
signature.

ERNEST H. MARCY.
